UNITED STATES PATENT OFFICE.

HOSMER TUTTLE, OF CEDAR RAPIDS, IOWA, ASSIGNOR OF ONE-HALF TO
SHELLEY TUTTLE, OF SALT LAKE CITY, UTAH.

MECHANICAL MOVEMENT FOR BICYCLES.

SPECIFICATION forming part of Letters Patent No. 650,343, dated May 22, 1900.

Application filed August 18, 1897. Serial No. 648,722. (No model.)

To all whom it may concern:

Be it known that I, HOSMER TUTTLE, a citizen of the United States, residing at Cedar Rapids, in the county of Linn and State of Iowa, have invented certain new and useful Improvements in Mechanical Movements for Bicycles, of which the following is a specification, reference being had therein to the accompanying drawings.

10 My invention relates to mechanical movements intended mainly for the propulsion of bicycles to take the place of the chain now generally used on safety-bicycles, and thereby reduce the expense and the amount of friction.

15 Although the construction of the movement can be used in connection with other machines, it is shown in the drawings in connection with a bicycle the frame of which may be of any suitable form. It comprises cranks 20 and crank-pins on the axle of the hind wheel, sprocket-wheels on the axle of the pedal-shaft, and forked connecting-rod to unite said axles, as described in Patent No. 564,665, granted to me July 28, 1896; but in this im-

25 provement the location of the hind cranks is within the side frames, the interlocking sprockets and the engaging or hooked ends of the forked connecting-rod are provided with antifriction-rollers, and special guides are 30 provided for said connecting-rod in place of suspension-links. The construction is shown in the accompanying drawings, in which—

Figure 1 represents a side view of a bicycle provided with a mechanism constructed in accordance with my invention, but showing only one of the forked rods. Fig. 2 represents, on a larger scale, a top view, partly in section, of the mechanism. Fig. 3 represents a side view of the same with the pedals and a portion of the horizontal frame and the upper frame removed. Fig. 4 represents, in top view and partly in section, the rear-wheel axle, its ball-bearings, crank-shaft, and connecting-rods. Fig. 5 is a side view of the rear portion of one of the forked connecting-rods, its crank-pin, ball-bearing cone, and locking device for said cone. Fig. 6 is a perspective view of the crank-pin. Fig. 7 is a transverse vertical section of one of the forked connecting-rods and its oscillatory and longitudinally-reciprocating ball-bearing support. Fig.

8 is a side view of the same. Fig. 9 is a longitudinal vertical section of the cross-head guide. Fig. 10 is a side view of a modified form of sprocket-wheel for engagement with the arms of the forked connecting-rods. Fig. 11 is an edge view of said sprocket-wheel. Fig. 12 is a top view of one of the branches of the forked connecting-rod adapted for engagement with said sprocket-wheel. Fig. 13 is a side view of the same. Fig. 14 is a side view of another branch of the forked connecting-rod provided with a curved and divergent removable tip for engagement with sprocket-wheels of larger diameter for greater speed.

In said drawings, A represents the seat-carrying standard of the frame, and A² the braces between the crank-shaft b, carrying the pedals B² and also the sprocket-wheels C and C² and the crank-axle d for the hind wheel E, said axle d having its ends received in ball-bearings a², mounted in the rear ends of the braces A² and protected by caps a³, which serve also as a lock-nut for the ballway.

75 Each end of the axle d has a crank-arm d², and each end of the hub of the wheel E has a similar crank-arm e²; but the arms e² are set at an angle of ninety degrees to each other. The arms d² e² of each crank are united together by a tubular crank-pin D, having lugs provided with parallel side faces and projecting from its ends that are received in corresponding cavities formed in the arms d² e², and a bolt D², passing through said arms and 85 through the crank-pin D, secures these parts together until it is desired to remove the wheel E for repairs. The pin D is grooved circumferentially to obtain a ballway to receive the inner face of the balls of the ball-bearing around it, and said balls are inclosed by the rear end of each forked connecting-rod, being adjustably retained in their seat by a ball-cone D³, having its periphery provided with serrations. To lock said cone, a 90 dog d³ is secured with a screw to the outer face of each connecting-rod and has its acute end made to engage with some one of the serrations on the periphery of the flange of the cone D³.

100 The sprocket-wheel C has projecting from its periphery at equal distances apart three

teeth c , provided on their end with antifriction-rollers r , to be received alternately into sprocket receivers or pockets f , placed on the front end of the lower branch of a forked connecting-rod F . A similar but inverted pocket f^2 is placed on the front end of the upper branch of the forked connecting-rod F to interlock with one of the antifriction-rollers r . It is evident that the arrangement of the interlocking parts can be inverted and that the sprocket-wheel can be provided with pockets c^2 in its periphery, as shown in Figs. 10 and 11, and the outer end of each branch of the forked connecting-rod be provided with an antifriction-roller r , as shown in Figs. 12, 13, and 14, to interlock with said pocket without departing from the spirit of my invention.

The distance between the front ends of the branches of the forked rod F is slightly more, but about equal to the diameter of the wheel C , with the addition of one of its sprockets or antifriction-rollers. Said distance is maintained by a vertical brace F^2 , uniting said branches, and divergent braces F' , uniting the pocketed ends to said brace F^2 . The front portion of the connecting-rod F may be suspended from the standard A by means of a link F^3 , as shown by dotted lines in Fig. 1, having its lower end pivoted to the vertical brace F^2 and its upper end pivoted upon a short shaft secured to the standard A ; but other means are shown in full lines in Figs. 1, 2, 3, 7, 8, and 9, and are mounted upon the side braces A^2 of the frame. Said means consist of a guide-plate H , brazed or otherwise secured along the inner face of each brace A^2 , and a cross-head I , centrally provided with a pin i , having its periphery screw-threaded and made to pass through the vertical brace F^2 of the forked rod. Ball-bearings are interposed between the pin i and the opening in said brace F^2 . Ball-bearings are also interposed between the cross-head I and the guide-plate H , the latter being provided with two ballway-pockets h in the top and also in the bottom and preferably only one ball in each pocket. The grooved cross-head I is also provided with grooved ballways adjustably retained by screws passing through the top and bottom thereof and have their ends closed by small plates i^2 , secured to the ends of said cross-head.

The above description relates to the left-hand half of the driving mechanism; but the mechanism on the right-hand side is exactly similar and consists of the forked connecting-rod G , having the brace G^2 , carried by cross-head and guide-plate, as above described. The lower branch of the connecting-rod G has a pocket g and the upper branch an inverted pocket g^2 . The sprocket-wheel C^2 is provided with three sprockets c^2 , provided with antifriction-rollers and equally spaced apart, but so timed relatively to the sprock-

ets c of the wheel C as to be about thirty degrees in the rear of each one of them.

The frame of the machine is provided with a forward brace A^3 , as usual.

In the operation of the mechanism the rocking up and down of the rear end of the connecting-rod F or G causes an inverse motion of the front end of said rod. In other words, when the left-hand crank-pin D on the rear end begins to ascend and passes above a horizontal line passing through the center of the rear shaft its front end descends and its pocket f^2 receives into engagement one of the uppermost sprocket-teeth, and said sprocket-tooth in its revolution pulls upon the rod F and continues to revolve the rear axle d . When the crank-pin D descends below the center of the crank-shaft d , the front end of the rod F ascends and its pocket f receives into engagement the bottom sprocket-tooth of the wheel C , and said sprocket-tooth pushes the connecting-rod F rearwardly and continues to revolve the rear axle d .

As there must necessarily be some moments in which the pockets of the rod F are not in engagement with the antifriction-roller of either a top or a bottom sprocket-tooth, the duplication of the mechanism is required to actuate the rear crank-axle during these intermediate movements. The sprocket-teeth are preferably made to project slightly on one side of the sprocket-wheel, so that the body of the latter will not be in the way of the hooked ends of the connecting-rods, and said teeth can be made shorter. As there is only one tooth or at the most a portion of two teeth in engagement with the connecting-rods and said teeth are provided with antifriction-rollers, the friction is reduced to the minimum possible.

The diameter of the sprocket-wheels and the number of teeth they are to carry can be selected according to the speed of motion that may be desired.

Having now fully described my invention, I claim—

In a mechanical movement for bicycles, the combination of the axle of one of the carrying-wheels, two crank-pins carried by said axle, two branched connecting-rods having at one end two oppositely-disposed sprocket-receivers, sprocket-wheels having teeth for engagement with the branched connecting-rods, a brace uniting the branches of said rods, a guide-plate, and a cross-head embracing said plate and having a pin revolubly connected with the branched connecting-rod substantially as described.

In testimony whereof I affix my signature in presence of two witnesses.

HOSMER TUTTLE.
